UNITED STATES PATENT OFFICE.

JAMES H. JOURDAN, OF NEW YORK, N. Y.

GAS-GENERATOR.

943,601.

Specification of Letters Patent. Patented Dec. 14, 1909.

Application filed March 14, 1908. Serial No. 421,180.

To all whom it may concern:

Be it known that I, JAMES H. JOURDAN, a citizen of the United States, residing at Brooklyn borough, New York city, in the county of Kings and State of New York, have invented certain new and useful Improvements in Gas-Generators, of which the following is a specification.

The generator, in the form shown in the drawing, is of the style ordinarily known as the Williamson improved gas generator, described and illustrated in Letters Patent of the United States, No. 767,217, issued August 9, 1904, although the pipe and valve connections, which more particularly form the subject matter of the present invention, can be applied to gas generators of other types in which it is desirable to control the flow of the blast through various parts of the generator structure, and control the flow of gases from one part of the generator to the other in the manufacture of water gas. In practice, it has been found that it is frequently difficult to maintain a suitable temperature in all portions of the generator structure, for the reason that it frequently happens that the carbureter will be overheated and the superheater underheated, or vice versa, so that the heat will be wasted in certain parts of the structure with a consequent waste of hydro-carbon oil and imperfect formation of the resulting gas. Another objection to gas generators of the ordinary construction is due to the fact that in firing the charge of fuel in the generator it is necessary for the blast to travel through the carbureter and the superheater prior to its discharge up the flue, which devious path of travel necessitates the employment of a heavier blast in firing than would otherwise be necessary.

The object of the present invention is to so improve the construction of standard generators of the Williamson and similar types, by the provision of suitable passages and valves, that the fuel body can be fired independently of the heating of the rest of the generator structure, and so that the carbureting and superheating chambers can be heated independently of each other.

Another object of the invention is to regulate the passage of the decomposed steam through the generator structure in such manner that the gases, generated by the decomposition of the steam, can be made to flow through both the carbureter and super-

heater; or, in cases where the carbureter is by-passed, immediately from the fire chamber into the superheater. In by-passing the carbureter, hydro-carbon vapors only will pass through the carbureter and be highly volatilized therein prior to admixture with the gases generated by the decomposition of steam, which method of charging the gas with illuminating constituents will be found desirable under certain conditions.

The device is one which enables fuel to be saved by concentrating the heat to such portions of the structure only as require heating, so that the different chambers of the structure will be kept at a temperature best suited to produce the most satisfactory results.

The invention consists in the features of construction and combination of parts hereinafter described and claimed.

The drawing is a sectional elevation of the gas generator of the Williamson type, showing the arrangement of passages and valves constituting the subject matter of the present invention.

The generator is of the usual cylindrical form, and comprises a fire chamber 1 provided with an arch wall 2, above which are located intermediate chambers 3 and 4 having openwork arch walls 5 and 6, respectively. The arch wall 5 forms the floor of the carbureter 7, and the arch wall 6 forms the floor of the superheater 8. The carbureter and superheater are filled with the usual checker brickwork and are separated from one another by a vertical partition wall 9. Immediately above the carbureter is a mixing chamber 10, and immediately above the superheater is a discharge chamber 11, from which extends a lateral discharge passage 12 and a vertical flue 13 which extends through the solid roof 14 of the generator structure. The fire chamber is provided with grate bars 15, below which are located the usual blast openings 16. The body of the generator is of the usual formation, and further detailed description is deemed unnecessary.

Adjacent the carbureter, and extending from a point in line with the top of the fire chamber up to a point in line with the floor of the mixing chamber, is a main conveyor pipe 17 which, at its lower end, connects with a laterally extending intake passage 18 which enters the fire chamber near the roof thereof and above the level of the

body of fuel contained therein. Connecting with the lateral passage 18, and immediately below the mouth of the pipe 17, is a vertical blast pipe 19 which connects with the horizontal blast header 20 extending immediately beneath the floor of the fire chamber, below the grate bars therein, from which blast header the blast is discharged through blast arch walls 21 or in any other suitable manner. Air is supplied to the blast header through a port or passage 20^a leading to a suitable blower or other source of supply.

Immediately above the lower lateral passage 18 is an intermediate lateral pipe or passage 22 which enters the wall of the intermediate chamber 3, below the floor of the carbureter. The upper end of the pipe or passage 17 connects with a lateral pipe or passage 23, which pierces the walls of the mixing chamber 10. In order to control the flow of the blast and the constituent gases through the various passages, valves of any suitable type are provided. The lower passage 18 is provided with a valve 24; the intermediate lateral passage is provided with a valve 25; and the upper lateral passage is provided with a valve 26. As shown in the drawing, these valves are of wedge formation, but other styles of valves, adapted to withstand excessive heat, can be employed. The pipe 17, above the opening of the intermediate passage 22, is provided with a valve 27, and the upper end of the passage 17, above the upper lateral passage, is provided with a purge valve or cap 28 which regulates the direct discharge from the pipe or passage 17.

The flue passage 13 is adapted to be closed by a valve or cap 29. An upper steam supply pipe 31 is provided, which opens into the lower lateral passage, and a lower steam pipe 32 is provided, which opens into the blast header 20, which latter is provided with a valve 33 which controls the communication between the blast header 20 and the vertical blast pipe 19.

The present invention is not concerned with the means provided for regulating the supply of steam and blast to the fire chamber on the up and down runs, which regulation can be performed in any usual well known manner.

In use, in initially firing a body of fuel, the blast can be admitted below the fuel, and the valves 24, 27 and 28 thrown open, the remaining valves being closed, which regulation provides a direct passage for the blast up, through and out of the pipe 17, which direct blast serves to quickly bring the fuel to a state of incandescence. After the fuel has thus been initially kindled, the purge valve or cap 28 can be closed and the valve 26 opened, which directs the course of the blast into and down through the carbureter and up through the superheater, discharging

the heated air and gases through the flue passage 13. This regulation of the valves serves to heat the entire generator to the degree required for the gas making operation.

It is obvious that if additional valves were not provided the carbureter would be heated to a greater degree than the superheater, by reason of the fact that the blast is initially discharged into the carbureter, the walls and checkerwork of which will absorb a major portion of the heat units prior to the passage of the blast up through the superheater. Without proper regulation, the carbureter will tend to become overheated by the time the superheater has reached its proper heat, so that hydro-carbon oil or vapor introduced into the carbureter will be overheated, and, in large measure, turned into lamp black, thereby wasting the oil and impairing the illuminating qualities of the gas discharged from the generator. In these circumstances, it is desirable at times to by-pass the carbureter and admit a blast, with its heated units unimpaired, directly into the superheater. To accomplish this result, the valves 26 and 27 are closed and the valves 25 and 29 are opened, which directs the blast immediately through the intermediate chambers 3 and 4 and up through the superheater without materially affecting the temperature of the carbureter. The latter, having been heated to the desired degree, will thoroughly volatilize the hydro-carbon oils or vapors which, in the form shown, are admitted from a pipe 34 in the mixing chamber 10.

When steam is admitted to the incandescent charge of fuel, it will be decomposed into its constituent gases, hydrogen and oxygen, the latter of which will combine with the carbon of the fuel and pass off with the hydrogen in the form of carbon monoxid. These gases, when the carbureter is by-passed by the regulation of the valves, will mingle with the thoroughly volatilized hydro-carbon vapors, heated to the proper degree, prior to the passage of the commingled gases through the superheater, the temperature of which, as compared with the temperature of the carbureter, can be regulated by the action of the valves. This method of regulating the flow of the gases serves to secure a proper degree of temperature for each of the constituent elements, which is impossible in previous constructions in which the carbureter cannot be by-passed. If, after continued use, the carbureter should become cooled to any considerable degree, it can be quickly reheated by a third regulation of the valves. By closing the valves 27 and 29 and opening the valves 25, 26 and 28, the superheater can be by-passed and the heat units and products of combustion carried directly through

the carbureter and discharged from the top of the pipe 17, which serves to quickly heat up the carbureter without affecting the temperature of the superheater.

- 5 It will be seen from the foregoing description that the operator of the apparatus can fully control every portion thereof and regulate at will the passage of gases or air through the carbureter and superheater.
- 10 For instance, if the operator finds, at the end of a gas run, that it is not necessary to blast for the full period through the carbureter, he can by-pass that part of the apparatus, but just before completing the gas 15 making period he may reverse the valves and allow hydrogen gas to pass down through the carbureter for the purpose of carrying off the remaining oil vapors. Again the operator may direct the blast in 20 the ordinary manner through both carbureter and superheater, and by-pass the carbureter with the hydrogen gas for any part or all of the run. All of these operations make it possible to regulate the temperature 25 of the carbureter to a point that will be best suited to the character of the oil used. Finally, the by-passing of the carbureter with the hydrogen gas will allow a slower travel of the oils down through the carbureter 30 checkerwork, which will result in a more complete breaking up of the oils and in higher efficiency of candle power per gallon, and a reduction in the number of pounds of coal per thousand, and a general gain in 35 capacity.

What I regard as new and desire to secure by Letters Patent is:

1. In a structure of the class described, the combination of a fire chamber, a carbureter and a superheater, the latter being in communication with one another at one end only, a main passage leading from the fire chamber to the non-communicating end of the carbureter, said passage being further 40 provided with a direct discharge outlet, an intermediate passage leading from the first mentioned passage to the communicating end of the carbureter, valves in said passages for controlling the flow to either end 45 of the carbureter, and a valve for controlling the direct discharge from the main passage, substantially as described.
2. In a structure of the class described, the combination of a fire chamber, a carbureter and a superheater, the latter being in communication with one another at one end only, a main passage leading from the fire chamber to the non-communicating end of the carbureter, said passage being further 50 provided with a direct discharge outlet, an intermediate passage leading from the first mentioned passage to the communicating end of the carbureter, valves in said passages for controlling the flow to either end 55 of the carbureter, a valve for controlling the
- direct discharge from the main passage, and a valve in the main passage intermediate the connection thereof with opposite ends of the carbureter for enabling either the carbureter or superheater to be by-passed, substantially as described. 70
3. In a structure of the class described, the combination of a fire chamber, a carbureter and a superheater, an intermediate chamber between the fire chamber and the carbureter and superheater, said intermediate chamber being in communication with the carbureter and superheater and affording a passage from one to the other, a mixing chamber at the receiving end of the carbureter, a main passage leading from the fire chamber to the mixing chamber, an intermediate passage leading from the main passage to the intermediate chamber, a valve in the main passage controlling the flow to the mixing chamber, and a valve for controlling the flow from the main passage to the intermediate chamber for permitting the carbureter to be by-passed, substantially as described. 80
4. In a structure of the class described, the combination of a fire chamber, a carbureter and a superheater, an intermediate chamber between the fire chamber and the carbureter and superheater, said intermediate chamber being in communication with the carbureter and superheater and affording a passage from one to the other, a mixing chamber at the receiving end of the carbureter, a main passage leading from the fire chamber to the mixing chamber, an intermediate passage leading from the main passage to the intermediate chamber, a valve in the main passage controlling the flow to the mixing chamber, a valve for controlling the flow from the main passage to the intermediate chamber for permitting the carbureter to be by-passed, substantially as described. 85
5. In a structure of the class described, a fire chamber, an intermediate chamber and a passageway located above said fire chamber, a carbureter located above said intermediate chamber, a superheater located above said passageway, a mixing chamber located above said carbureter, and a discharge chamber located above said superheater, in combination with a main passage leading from the fire chamber to the mixing chamber, an intermediate passage leading from the main passage to the intermediate chamber, a valve in the main passage controlling the flow to the mixing chamber, a valve in the intermediate passage controlling the flow from the main passage to the intermediate chamber, for permitting the carbureter to be by-passed, a valve in the main passage inter- 100
- 105
- 110
- 115
- 120
- 125
- 130

mediate the aforesaid valves, and a purge valve for permitting direct discharge from the main passage, substantially as described.

6. In a structure of the class described, a fire chamber, an intermediate chamber and a passageway located above said fire chamber, a carbureter located above said intermediate chamber, a superheater located above said passageway, a mixing chamber located above said carbureter, and a discharge chamber located above said superheater in combination with a main passage leading from the fire chamber, a vertical passage leading from said main passage to a blast header, an intermediate passage lead-

ing from the main passage to the intermediate chamber, a valve in the main passage controlling the flow to the mixing chamber, a valve for controlling the flow from the main passage to the intermediate chamber, 20 for permitting the carbureter to be bypassed, a valve in the main passage intermediate the aforesaid valves, a valve in the blast header, and a purge valve for permitting direct discharge from the main 25 passage, substantially as described.
